[57] CLAIM

The ornamental design for a plant box, substantially as
shown and described.

DESCRIPTION

FIG. 1 is a perspective view of a plant box showing my
new design, with one end plate removed; and
FIG. 2 is a side elevation thereof.

The plant box is in the form of a trough provided with
at least one end plate. The trough is corrugated, and the
characteristic feature of the design resides in the fact
that the end plate has a flange and the flange is formed
complementarily to the corrugation of the trough.
